L. R. BARBER AND J. A. BAKER
SOLDERING IRON,
APPLICATION FILED DEC. 11, 1919.

1,357,606.

Patented Nov. 2, 1920.

UNITED STATES PATENT OFFICE.

LAUNCE R. BARBER AND JOSEPH A. BAKER, OF SHARON, PENNSYLVANIA.

SOLDERING-IRON.

1,357,606.

Specification of Letters Patent.

Patented Nov. 2, 1920.

Application filed December 11, 1919. Serial No. 344,263.

To all whom it may concern:

Be it known that we, LAUNCE R. BARBER and JOSEPH A. BAKER, citizens of the United States, residing at Sharon, in the county of Mercer and State of Pennsylvania, have invented certain new and useful Improvements in Soldering-Irons, of which the following is a specification.

This invention relates to soldering irons, 10 and more particularly to a soldering iron of the electrically heated type.

One of the main objects of the invention is to provide an iron of simple construction employing spaced carbon electrodes for 15 producing an arc for heating the top of the iron. Another object is to provide simple and efficient means for holding the electrodes and for adjusting one of them so as to vary the length of the arc. A further 20 object is to provide means whereby the electrodes may be readily renewed. Further objects will appear from the detailed description.

In the drawings:

25 Figure 1 is a central longitudinal section through a soldering iron constructed in accordance with our invention.

Fig. 2 is a detail of an instrument used 30 for adjusting the movable electrode.

Fig. 3 is a detail of the top portion of a modified form of iron partly broken away.

Fig. 4 is a section through the handle portion of the form illustrated in Fig. 3.

Fig. 5 is a detail of the electrode feeding 35 means.

Fig. 6 is a section taken on line 6—6 of Fig. 5.

Fig. 7 is a detail of the electrode holding 40 and adjusting head.

Referring to Fig. 1, the tip 1 is provided with a neck 2 threaded into one end of a barrel 3 of steel or other suitable material of high electrical conductivity. A plug 4 of electrical insulating material is threaded in 45 the other end of the barrel and receives a copper sleeve 5 through which is threaded a copper tube 6 provided on its outer end with a hand wheel 7 of electrical insulating material. Plug 4 is provided with an outer 50 annular flange which seats in a corresponding recess in a handle 8 of wood or other suitable material secured about the barrel, and sleeve 5 is connected by a contact plate 9 with one wire of a cord 10 leading from 55 a plug 11 of suitable type, the other wire of this cord being inserted through a suit-

able bore in the handle and connected to the barrel. By this means the tube 6 and barrel 3 may be readily connected to the opposite sides of an electric circuit.

The tip 1 is provided with an axial bore 12 extending from the inner end of neck 2, this bore communicating at its outer end with a concentric bore of less diameter which receives a relatively short electrode 13 of carbon frictionally secured therein. A carbon electrode 14 of great length relative to electrode 13 fits snugly in tube 6 so as to be frictionally held thereby. This electrode fits snugly through an annulus 15 of insulating and fire proof material secured in barrel 3 a short distance from the tip 1. The length of the arc may be varied by rotating tube 6 thus giving accurate control of the heating of the tip. This also provides means for accommodating wearing of the electrodes. Electrode 14 may be adjusted in tube 6 by means of the instrument shown in Fig. 2, as it wears away at its inner end.

In the modified form, barrel 3 is threaded into tip 1, the end of the barrel pressing tightly against an annular flange 17 of an electrode holder 18 seated in the tip. This holder carries the shorter carbon electrode 19 frictionally secured therein, the inner end of which is spaced from the longer electrode 20 frictionally secured in a holder 21 carried by a head 22 of electrical insulating material slidable in a slotted tube 23 extending centrally of barrel 3. This tube is provided with an enlarged outer end element 24 fitting snugly through a flanged sleeve 25 of insulating material secured to handle 8. Element 24, and consequently tube 23, is held against movement through the sleeve by an outer flange 26 positioned adjacent the outer end of the sleeve, and a nut 27 threaded on the tube adjacent the inner end of the sleeve. Member 24 is provided with 95 an annular groove 28 which receives the inner portion of a brush 29 mounted in a bore extending radially of the sleeve and receiving one wire 30 of a cord 31, this wire being electrically connected to electrode 20. 100 Through the medium of brush 29, element 24, and tube 23. The other wire 32 of the cord extends through a bore in handle 8 and is connected to barrel 3.

The outer ends of the arms of head 22 are 110 grooved to form threads 22a which are adapted to engage similar threads 33 formed

on the inner surface of barrel 3 for a portion of the length thereof. A cap 34 of electrical insulating material is secured by a screw 35 over the outer end of tube 23, this cap being provided with an inner squared lug 36 fitting into a corresponding recess in the outer end of the tube. By turning cap 34 the head 22, and consequently electrode 20, may be adjusted so as to vary the length 10 of the arc between the electrodes as conditions may require.

As will be understood, as suggested herein, there may be slight changes made in the construction and arrangement of the details 15 of our invention without departing from the field and scope of the same, and we intend to include all such variations, as fall within the scope of the appended claims, in this application in which the preferred 20 forms only of our invention are disclosed.

What we claim is:

1. In a soldering iron, a tip having a recess, a flanged electrode holder mounted in said recess, an electrode removably secured 25 in said holder, a barrel detachably secured in the recess of the tip and bearing against

the flange of said electrode holder, an electrode mounted in the barrel in spaced relation to the first mentioned electrode and insulated from the barrel, and means for connecting said barrel and the electrode mounted therein to the opposite sides of an electric circuit. 30

2. In a soldering iron, a barrel, a tip carried thereby, an electrode carried by said tip, 35 a tube mounted in the barrel for rotation and electrically insulated therefrom, a head of electrical insulating material carried by said tube and slideable longitudinally thereof, an electrode carried by the head and fitting snugly through the inner end of the tube, coaxing means carried by the head and the barrel for adjusting said head longitudinally of the tube upon rotation of the latter, and means for connecting the tube 40 and the barrel to the opposite sides of an electric circuit. 45

In testimony whereof we affix our signatures.

LAUNCE R. BARBER.
JOSEPH A. BAKER.
